UNITED STATES PATENT OFFICE.

WILLIAM B. BROOKS, OF WATERBURY, CONNECTICUT.

METHOD OF MAKING FRAMES FOR HARNESS-BUCKLES.

SPECIFICATION forming part of Letters Patent No. 369,430, dated September 6, 1887.

Application filed April 23, 1887. Serial No. 235,837. (No model.)

To all whom it may concern:

Be it known that I, WILLIAM B. BROOKS, residing at Waterbury, in the county of New Haven and State of Connecticut, have invented certain new and useful Improvements in the Method of Making Frames for Harness-Buckles; and I do declare the following to be a full, clear, and exact description of the same, reference being had to the accompanying drawings, which form a part of this specification.

My invention relates to an improved method of making frames for harness-buckles, the object being to produce with great economy over the old methods frames having tongue guards and a tongue-seat.

With these ends in view my invention consists in a method of making frames for harness-buckles, consisting in stamping a frame-blank out of sheet metal; then piercing out the center of such blank, and then developing tongue-guards and a tongue-seat, respectively, upon and in such pierced blank by subjecting the same to pressure between suitable dies, which also transform it into a buckle-frame.

In the accompanying drawings, Figure 1 is a plan view of the blank in its first stage. Fig. 2 is a view thereof in central longitudinal section. Fig. 3 is a plan view of the blank after its center has been pierced out. Fig. 4 is a view of such pierced blank in central longitudinal section. Fig. 5 is a plan view of the buckle-frame developed from such pierced blank by subjecting it to pressure between suitable dies and showing the tongue-seat. Fig. 6 is a reverse plan view of such frame, showing the tongue-guards. Fig. 7 is a view

of the frame in central longitudinal section. Fig. 8 is a plan view of the completed buckle, and Fig. 9 is a view thereof in central longitudinal section.

The blank A is first died out from suitable wrought, sheet, or plate metal, and conforms in general outline to the edge of a buckle-frame. The center of this blank is then pierced out on a line conforming to the inner outline of a buckle-frame and the pierced blank B produced. This pierced blank is then subjected to pressure between highly-polished steel dies adapted to shape it, harden and polish it, and so develop the frame C, having elevated tongue-guards D and a depressed tongue-seat, E, such guards and seat being produced by a suitable construction of the dies.

Having fully described my invention, what I claim as new, and desire to secure by Letters Patent, is—

A method of making harness buckle frames, consisting in first stamping out a blank from sheet or plate metal, then piercing out the center of such blank, and then developing tongue-guards and a tongue-seat, respectively, upon and in such pierced blank by subjecting the same to pressure between suitable dies, which also transform it into a buckle-frame, substantially as set forth.

In testimony whereof I have signed this specification in the presence of two subscribing witnesses.

WM. B. BROOKS.
